Primary Examiner — Anhdao Doan(74) Attorney, Agent, or Firm — Inventech Patent Services, LLC(57) CLAIM

I claim the ornamental design for a cosmetic steamer, as shown and described.

DESCRIPTION

FIG. 1 is a perspective view of a cosmetic steamer, showing my new design;

FIG. 2 is a front elevational view thereof;

FIG. 3 is a right-side elevational view thereof;

FIG. 4 is a rear elevational view thereof;

FIG. 5 is a left-side elevational view thereof;

FIG. 6 is a top plan view thereof; and,

FIG. 7 is a bottom plan view thereof.

The broken lines immediately adjacent the shaded areas represent the bounds of the claim, while all other broken lines are directed to environment and are for illustrative purposes only; the broken lines form no part of the claimed design.
